WINDOW SAFETY BELT SUPPORT

Ben S. Nelson, Oak Park, Ill.

Application July 5, 1945, Serial No. 603,331

5 Claims. (Cl. 189—76)

1

The present invention relates to window structures and more particularly to improved facilities for supporting a safety belt of the type used by window washers from a window sash.

In many modern office and factory buildings, installations of solid steel window sash have been made with the intent that the windows should be cleaned from the building interior by reversing each window ventilating section and reaching through the open ventilator to clean the outside of the glass in the adjacent sections. In the larger installations, particularly in buildings with high ceilings, the windows are made up in sections, with as many as seven vertical sections, thus rendering it impossible to clean the outside window surfaces from the interior of the building. Designed to be cleaned from the inside, no provisions are made in such installations for the attachment and support of window washers' safety belts. Moreover, in the usual installation of this character only a small strip of metal at each side of the sash, having a width of approximately $\frac{1}{4}$ " to $\frac{5}{8}$ ", is left between the masonry column and the glass panes in the first sections of the sash, the balance of each sash side being embedded in the adjacent concrete, stone or brick column to hold the sash permanently in place. Thus conventional methods of attaching the belt lugs cannot be used. Since the development of window cleaning as an industry, it has become common practice for window washers to work on the outside of the windows, including windows of the type mentioned, due to the ability of the washers to work faster and to their inability to reach the outside window surfaces from the interior of a building. The lack of safety belt supports on windows of the character mentioned has resulted in numerous serious accidents and fatalities.

It is an object of the present invention, therefore, to provide for use with a window of the character described, improved facilities for supporting a safety belt or the like.

It is another object of the invention to provide an improved safety belt support which may be installed upon the window sash of existing window installations of the character mentioned.

It is a further object of the invention to provide safety belt supporting facilities of the character described which are of simple and rugged construction, and may be easily and economically installed.

The invention, both as to its organization and method of operation, together with further objects and advantages thereof, will best be under-

2

stood by reference to the following specification taken in connection with the accompanying drawing, in which:

Fig. 1 is an elevational view of a window structure of the steel sash type having the present improved safety belt supporting facilities associated with the two sides thereof;

Fig. 2 is an enlarged fragmentary view better illustrating one of the supports shown in

10 Fig. 1;

Fig. 3 is a sectional view taken along the lines 3—3 in Fig. 2.

Fig. 4 is an interior view of the support shown in Fig. 2;

15 Fig. 5 is a sectional view taken along the lines 5—5 in Fig. 2, assuming that Fig. 2 is a complete enlarged view of a portion of Fig. 1; and

Fig. 6 is a sectional view like Fig. 3 but illustrating the arrangement of the parts prior to 20 complete assembly.

Referring now to the drawings and more particularly to Fig. 1 thereof, the present improved safety belt supporting facilities are there illustrated in their association with a multi-section window 10 of the steel sash type which is provided in a suitable window aperture of a building 14 constructed of masonry such, for example, as brick, concrete, or stone. The window is comprised of a stationary upper section 12 two window sections high and three window sections wide, and a lower ventilating section 11 which is three window sections high and a like number of sections wide. In accordance with conventional practice the ventilating section 11 is pivotally supported as indicated at 13 to permit a portion of the window opening to be opened and closed for ventilating purposes. The window panes of this movable section are, of course, carried by a separate frame which is pivotally supported by

25 the main window frame 18 of steel construction and forming a permanent part of the building wall in which the window 10 is provided. As best shown in Fig. 3 of the drawing, this frame is provided at its outer sides with a flange 18d

30 which is embedded in the masonry work supporting the window structure. It is also provided with suitable cross and vertical muntins forming the sash sections and having internal shoulders against which the window panes are supported. These shoulders are identical, those provided by the muntins 18a, 18b and 18c being shown in Figs. 3 and 5 of the drawings.

As will be evident from an inspection of the window shown in Fig. 1 of the drawing, cleaning 35 of the exterior surfaces of the window from the

interior thereof is practically impossible since it involves reaching out through the ventilating space afforded by the movable window section 11 in order to reach the outer surfaces of the window panes forming the stationary section 12 of the window. It will also be apparent from a consideration of Fig. 3 of the drawing, that an inadequate portion of the frame 18 is available between the inner surface 14a of the masonry column and the edge of the muntin along this column to permit a safety belt support to be securely mounted thereon. Specifically, the width of the exposed side portion of the sash is usually of the order of $\frac{1}{4}$ ", which obviously is inadequate for the purpose mentioned. Moreover, the thickness of the masonry column exteriorly of the frame flange 18d is usually of the order of several inches, thus effectively rendering this flange unavailable as a base upon which a safety belt support may be mounted.

In accordance with the present invention, the above difficulties are obviated by providing safety belt supports within the window pane area of two opposed and horizontally aligned sections 12a and 12b of the frame 18. These supports are adapted for interlocking engagement with the usual safety belt hooks 16 provided at opposite ends of a window washer's safety belt indicated at 17. The supports are of identical construction.

In brief, that mounted within the area of the window sash section 12b comprises a structural member 20 of channel cross section which is mounted upon the sash or frame against the shoulder afforded by the vertical muntin 18a provided along the side of the sash adjacent the masonry column, and comprises a web portion 20a and two side flanges 20b and 20c. As best shown in Fig. 5 of the drawing, the upper and lower ends of the web portion 20a respectively seat against the internal shoulders afforded by the upper and lower muntins 18b and 18c of the sash. The flange 20b of this member is arranged at an angle of slightly more than 90 degrees relative to the web portion 20a of the member. This flange is adapted to be clamped to the muntin 18a of the frame 18. To this end, threaded studs 21 are welded or likewise rigidly mounted upon the sash 18 along the muntin 18a. These studs are appropriately spaced to extend through similarly spaced openings in the flange 20b. Nuts 22, lock washers 23 and plain washers 23a are disposed on the studs 21. The nuts 22 are employed to draw the flange 20b into clamping engagement with the side of the frame 18. During this clamping operation, the end portions of the web 20a are forced into seating engagement with the internal shoulder provided along the upper and lower muntins 18b and 18c. As thus mounted within the opening of the sash section 12b, the structural member 20 shortens the horizontal dimension of this sash opening by an amount equal to its width and also occupies the shoulder along the muntin 18a which normally affords support for one edge of a window pane. In order to provide an auxiliary window pane supporting shoulder to take the place of that along the muntin 18a, a plate or strip 24 is fixedly mounted upon the web 20a of the member 20 to cooperate with the flange 20c of this member in supplying the required seat for the edge of a window pane. Preferably, this plate is spot welded to the web 20a as indicated at 24a at various points along the length thereof. As will be evident from Fig. 3 of the drawing, the inner supporting surface of the plate 24 is co-planar with the supporting

shoulders of the muntins 18b, 18c and 18e and in cooperation with these shoulders may be employed to support a window pane 19 of smaller area than the original pane area of the sash section 12b. This pane may be held in place against the internal shoulders of the three muntins 18b, 18c and 18e and the plate 24 by means of putty or the like.

The web 20a of the member 20 is also employed to support an attachment 15 having lugs 15a adapted for engagement with a safety belt attachment 16. More specifically, the attachment 15 is provided with a base bolted to the web 20a by means of bolts 25 and has hook lugs 15a formed integral therewith. The belt attachment or hook 16 is of conventional construction, being slotted as indicated at 16a for interlocking engagement with the headed lugs 15a and being provided with the usual locking spring 16b for preventing disengagement of the attachment from the upper lug 15a. This spring carries a finger loop 16c which may be used to retract the spring and thus permit removal of the attachment from the lugs 15a. At its lower end, the attachment 16 is provided with a belt loop 16d to which one end of the safety belt 17 may be connected.

From the above explanation, it will be understood that the present improved safety belt supporting facilities may readily be installed in an existing window installation without destruction or removal of the installation and in an entirely simple manner. Thus, to install the two supports illustrated in Fig. 1 of the drawing, it is only necessary to remove the panes from the window sash sections 12a and 12b, fabricate the studs 21 to the sides of the sash, assemble the member 20 and the parts carried thereby upon the studs and clamp the flange 20b of this member against the side of each sash upon which the studs 21 are mounted. Following this, a window pane 19 cut to the required dimensions may be mounted within the opening of each of the sash sections 12a and 12b to complete the job. All of the described operations may be performed from the interior of the building in which the window 10 is provided. In this regard it will be understood that the parts 15 and 24 are preassembled upon the supporting member 20 before this member is installed in a window sash. The described facilities furnish exceedingly rugged support for a safety belt attachment 16. Thus, not only is the member 20 rigidly mounted upon the window sash by means of the studs 21, but the ends thereof are interlocked with the associated upper and lower muntins 18b and 18c to provide additional support for any weight imposed upon the member 15. This dual support of the member 20 effectively eliminates any possibility of failure of the structure.

60 While there has been described what is at present considered to be the preferred embodiment of the invention, it will be understood that various modifications may be made therein which are within the true spirit and scope of the invention as defined in the appended claims.

I claim:

65 1. A safety belt support adapted to be mounted upon a metal window sash having an internal shoulder for supporting a window pane, comprising a structural member having a web seating upon the shoulder along one side of said sash so that one dimension of the window opening is shortened by the width of said web and having ends seating against the shoulders along two other sides of said sash, said member having a

flange extending from said web along one side thereof, means for clamping said flange to said sash along said one side thereof, said flange extending from said web at an angle of slightly more than ninety degrees, whereby the ends of said web are forced into seating engagement with the shoulders along said two other sides of said sash as said flange is clamped to said one side of said sash, said member including means providing a window pane supporting shoulder laterally displaced from the shoulder along said one sash side which together with the shoulders along said two other sides and the fourth side of said sash is adapted to support a window pane of smaller area than the original window area of said sash, and an attachment carried by said web and provided with means adapted for engagement with a safety belt attachment.

2. A window construction supported by a masonry structure, comprising a metal window sash having a flange along one side thereof embedded in said masonry structure and having an internal shoulder for supporting a window pane, a structural member mounted upon the shoulder along said one side of said sash so that one dimension of the window sash is shortened by the width of said member, means carried by said member to provide a window pane supporting shoulder which together with the shoulders along the other three sides of said sash support a window pane of smaller area than the original pane area of said sash, and a hook fastened to said member engageable with a safety belt.

3. A window construction supported by a masonry structure, comprising a metal window sash having a flange along one vertical side thereof embedded in said masonry structure and having an internal shoulder for supporting a window pane, a structural member mounted upon said sash against the shoulder along said one side of said sash so that one dimension of the window sash is shortened by the width of said member, the ends of said member seating against the shoulders along horizontal parts of said sash, said member including means defining a window pane supporting shoulder laterally displaced from said one sash side which together with the shoulders along the other three sides of said sash support a window of smaller area than the original window area of said sash, and a hook fastened to said member engageable with a safety belt.

4. A window construction supported by a masonry structure, comprising a metal window sash having a flange along one vertical side thereof

55

embedded in said masonry structure and having an internal shoulder for supporting a window pane, a structural member having a web seating upon the shoulder along said one side of said sash so that one dimension of the window opening is shortened by the width of said web and having ends seating against the shoulders along the horizontal sides of said sash, said member having a flange extending from said web along one side thereof, means for clamping said flange to said sash along said one side thereof, said flange extending from said web at an angle of slightly more than ninety degrees, whereby the ends of said web are forced into seating engagement with the shoulders along said horizontal sides of said sash as said flange is clamped to said one side of said sash, said member including means providing a window pane supporting shoulder laterally displaced from the shoulder along said one sash side which together with the shoulders along the other three sides of said sash support a window pane of smaller area than the original window area of said sash, and an attachment carried by said web and provided with means adapted for engagement with a safety belt attachment.

5. A window construction supported by a masonry structure, comprising a metal window sash having a glass pane opening therein framed by horizontal and vertical metal frame portions, a structural member in said opening which reduces the open area thereof and having a flange secured to a vertical frame portion and a web extending into said opening and supported on horizontal frame portions, said structural member having a shoulder extension thereon extending laterally relative to said web and into said opening to receive a glass pane thereon and acting together with the metal frame portions to support said glass pane, and safety belt supporting attachments secured to the web of said structural member.
